UNITED STATES PATENT OFFICE.

MARY BACON MARTIN, OF NEW YORK, N. Y.

PROCESS OF STAINING PAPER, &c.

SPECIFICATION forming part of Letters Patent No. 321,234, dated June 30, 1885.

Application filed December 10, 1884. (No specimens.)

To all whom it may concern:

Be it known that I, MARY BACON MARTIN, of the city, county, and State of New York, have made an invention of certain new and 5 useful Improvements in the Process of Staining Paper and other Materials, and of a new article of manufacture produced thereby; and I do hereby declare that the following is a full, clear, and exact description and specification 10 of the same.

The object of this invention is to produce upon paper and other suitable materials a clouded colored surface, with or without the aid of bronze, and the process and products 15 thereof are specified in the claims at the close of this specification.

In order that the same may be fully understood, I will proceed to describe the best mode in which I have thus far practiced my process.

20 The colors which are used by me are what are commonly known as "water-colors," and consist of pigments mixed with water (with or without sizing) to such tint as may be found expedient. The color chosen is applied 25 in a wash to the paper to be stained, the application being made by means of a brush or by means of a roller whose surface is formed of bristles or hairs, so that it is in substance a roller-brush. Immediately after the color is 30 applied a roller covered with blotting-paper, so as to form an absorbent, is run over the washed surface, the practical effect of which is to absorb the surplus color and to leave the residue irregularly distributed, so that the paper 35 has a clouded colored surface. The absorbing roller also partially dries the paper, so that it is left in a damp condition. The paper is permitted to dry, and, if desired, is flattened by a slight pressure during drying.

40 If desired, two or more washes of colors differing from each other may be applied in succession to the paper, the application of each wash being succeeded by the absorption of the surplus by means of the absorbing roller 45 or its substitute for that purpose.

If the paper is to be bronzed as well as colored by the above-described process of washing and succeeding absorption, the bronze should be applied either in a liquid or in a 50 dry powdered condition to the paper before the application of the color, or before the application at least of the last coat of color, and

the succeeding coat or coats of color should have ox-gall or some substitute therefor mixed with it in order to insure the proper covering 55 of the bronzed surface before the absorbing operation is effected.

The sheets which have been colored by means of pigments mixed with water without ox-gall or sizing may have the colors fixed, 60 without glazing, by the application of one of the well-known fixatives—such, for example, as the "charcoal fixative" used for fixing crayon-drawings.

If deemed best, the color and bronze may be 65 applied simultaneously to the paper, or the bronze may be applied after all the coloring, and may be fixed to the paper or other material by a sizing or other fixative. The surplus color also may be absorbed by means of 70 blotting-paper in the sheet or in the form of a pad instead of by a blotting-roller.

The paper which I have used with success is Whatman's rough drawing-paper; but the invention is not restricted to the use of paper, 75 as leather—such as that used in wall decoration—Morocco leather, and book-binders' cloth may be colored, or colored and bronzed, by the above-described process in the same manner as paper, the coloring being effected either before 80 or after the material is sized, as deemed best. The process also is not restricted to water-colors or to flexible materials. Thus, plastered walls may be colored by the same process with oil-colors. In this case the oil-colors are thinned 85 with spirits of turpentine and applied to the wall with a brush, and the surplus is subsequently absorbed by running a blotting-paper roller over the colored surface.

The practical effect of the above-described 90 process is the production of a clouded colored surface entirely distinct from the effects produced by the process commonly called "marbling;" and the material produced is highly useful for decorative purposes, and may be 95 used for decorating the walls of rooms, for book-binding, for covering paper-boxes, and for other purposes to which it is applicable.

I claim as my invention—

1. The process, substantially as before set 100 forth, of coloring material by the application thereto of a wash of color, and by subsequently absorbing the surplus color, substantially as before set forth.

2. The process, substantially as before set forth, of coloring and bronzing material by the application thereto of a wash of color, by absorbing the surplus thereof, and by the application to the material of bronze, all substantially as above set forth.

3. As a new article of manufacture, material colored with a wash of color, the surplus of which has been removed by absorption, to substantially as before set forth.

4. As a new article of manufacture, a bronzed material colored with a wash of color, the surplus of which has been removed by absorption, substantially as before set forth.

In witness whereof I have hereto set my hand this 4th day of December, A. D. 1884.

MARY BACON MARTIN.

Witnesses:

WILLIAM J. KELLY,
FRED INGRAHAM.
